(57) CLAIM

The ornamental design for a suction hook, as shown and described.

DESCRIPTION

FIG. 1 is a perspective view of a suction hook showing our new design;

FIG. 2 is a front view thereof;

FIG. 3 is a rear view thereof;

FIG. 4 is a side view thereof;

FIG. 5 is a top view thereof; and,

FIG. 6 is a bottom view thereof.

The broken lines shown in the drawings depict portions of the suction hook and form no part of the claimed design.

1 Claim, 6 Drawing Sheets
